[57] CLAIM

The ornamental design for a tote box for fruit or the like, as shown and described.

DESCRIPTION

FIG. 1 is a top perspective view of a tote box for fruit or the like showing our new design;

FIG. 2 is a top plan view;

FIG. 3 is a bottom plan view;

FIG. 4 is an elevational view of one side;

FIG. 5 is an elevational view of one end;

FIG. 6 is an elevational view of the side opposite the side shown in FIG. 4;

FIG. 7 is an elevational view of the end opposite the end shown in FIG. 5;

FIGS. 8 and 9 are side and end elevational views respectively, corresponding respectively to the side view shown in FIG. 4 and the end view in FIG. 5, and showing a modified form of our new design wherein the only modification is the provision of the openings or perforations shown; and where in said modified form of the design the side opposite that shown in FIG. 8 and the end opposite that shown in FIG. 9, which correspond respectively to the side shown in FIG. 6 and the end shown in FIG. 7, are also provided with openings or perforations like those in FIGS. 8 and 9;

FIG. 10 is an enlarged cross sectional view taken along the line 10—10 of FIG. 4; and

FIG. 11 is an enlarged cross sectional view taken along the line 11—11 of FIG. 4.
